Box Flap Holder
Attorneys:

UNITED STATES PATENT OFFICE.

HUGO J. KROETZ, OF MILWAUKEE, WISCONSIN.

BOX-FLAP HOLDER.

Application filed October 9, 1923. Serial No. 667,563.

To all whom it may concern:

Be it known that I, HUGO J. KROETZ, a citizen of the United States, and resident of Milwaukee, in the county of Milwaukee and 5 State of Wisconsin, have invented certain new and useful Improvements in Box-Flap Holders; and I do hereby declare that the following is a full, clear, and exact description thereof.

10 This invention relates to box flap holders.

In pasting the flaps of boxes in position, difficulty has been experienced, due to the inability of the operator to successfully hold the flaps down and paste them firmly in position. 15 Usually the operator has found it necessary to use other portions of his body, as his hands, for instance, a knee, to retain the flaps in position while he pastes them down. It will be readily appreciated that 20 in large shipping departments this mode of operation has needlessly wasted a large amount of time.

This invention is designed to overcome the above noted defect, and objects of such invention are to provide a box flap holder which may be instantly applied to the box to retain the flaps temporarily in position while they are being pasted, which may be readily manipulated, which is adjustable to 30 fit boxes of different sizes, and which is of simple construction and attractive appearance.

An embodiment of the invention is shown in the accompanying drawings, in which:—

35 Figure 1 is a side elevation of the device, showing the box, upon which it is positioned, in dotted lines.

Figure 2 is a vertical sectional view through the device.

40 Figure 3 is a sectional view through the horizontally extending arms, showing a modified form of construction.

Figure 4 is a fragmentary side view, partly in section, of the construction shown 45 in Figure 3.

The device comprises a body portion 1 which is of channel shape and has upwardly extending flanges 2. If desired the body portion 1 may be thickened, as indicated at 50 3, adjacent its central portion, and is provided with a threaded aperture 4 through such thickened portion. The flanges 2 are apertured and receive the inwardly projecting parallel arms 5 and 6 of U-shaped members formed preferably from rods. These

members 5 and 6 are downwardly turned, as indicated at 7 and 8, respectively.

Above the arms 5 and 6 a pad 9 of leather, or similar material, is located between the flanges 2 and is adapted to bear downwardly 60 against said rods. A clamping block 10 is positioned above the pad and loosely fits between the flanges. This clamping block is provided with an aperture 11 therethrough adapted to loosely receive the threaded stem 65 12 of a screw, such screw engaging the threads of the aperture 4 in the body portion 1.

The screw is provided with a manipulating handle 12, which is preferably of such 70 size as to be easily grasped by one hand of the operator when adjusting or positioning the device. This handle 12 may be in the form of a torus shaped disc, if desired, and may be clamped between suitable washers 75 carried by the screw. A pair of nuts 13 retain the handle in position in binding relation to the screw,—one of such nuts acting as a lock nut.

Obviously, the rods 5 and 6 may be made 80 of any desired length to accommodate different sizes of boxes. However, if it is desired to supply a medium length set of rods, it is merely necessary to provide extension members, which are in the form of rods 14 and which carry sleeves 15 at their outer end. These sleeves 15 are locked to the rods by means of set screws 16 and are provided with set screws 17 adapted to engage the rods 5 or 6, as the case may be, and to lock such 90 rods rigidly with respect to the extension rod 14. It is preferable to provide the sleeves 15 with flat faces 18, as shown in Figure 3, so as to readily clear the adjacent rods.

95 In using the device, the portions 7 and 8 are adjusted to the desired width, and the hand wheel 12 is rotated to cause the clamping block 10 to press downwardly and to thus bind the rods in their adjusted position. When so adjusted, the device may be readily slipped downwardly upon a box, as indicated in dotted lines at 19 in Figure 1, with the portions 7 and 8 engaging the side walls of the box and retaining the device in 100 position. The flaps 20 are held downwardly and the ends of such flaps may be readily pasted. Thereafter the device may be removed and the central pasting strip positioned upon the box. It is to be noted that 110

the body portion 1 bears downwardly directly against the adjacent central portion of the top of the box, and thus engages the free ends of the flaps 20 and retains them in position.

After the device has been set, it may be quickly applied to the boxes without any resetting, as it may be slipped downwardly upon the box, thus forcing the flaps into position, and may be as quickly removed therefrom.

It will thus be seen that a box flap holder has been provided, which is extremely serviceable, which may be readily applied, and which is of attractive and pleasing design.

Although the invention has been described in considerable detail, it is to be understood that it may be variously embodied and is therefore to be limited only as claimed.

20. I claim:—

1. A box flap holder comprising a body portion, a pair of rods slidably carried thereby and terminating in downwardly extending portions adapted to grip the sides of a box, and a handle having a screw threaded portion extending at right angles to said rods and into said body portion for clamping said rods in relatively adjusted position with respect to said body portion.

25. 2. A box flap holder comprising a body portion having apertured side flanges, a pair of rods passing through the apertures in said flanges and terminating in down-

wardly extending portions adapted to grip the sides of a box, and clamping means located between said flanges and adapted to bind said rods in adjusted position.

3. A box flap holder comprising a body portion having upstanding side flanges provided with apertures, rods slidably passing through said apertures and terminating in a downwardly extending end portion adapted to grip the sides of a box, a clamping block loosely positioned between said flanges, a screw passing through said clamping block and threaded into said body portion, and a handle carried by the upper end of said screw.

4. A box flap holder comprising a body portion having upstanding side flanges provided with apertures, a pair of U-shaped rod members having parallel arms slidably received within said apertures and terminating in downwardly extending portions adapted to grip the sides of a box, a clamping member positioned between said flanges and above said rods, a screw loosely passing through said clamping member and threaded to said body portion, and a manipulating handle carried by the upper end of said screw.

In testimony that I claim the foregoing I have hereunto set my hand at Milwaukee, in the county of Milwaukee and State of Wisconsin.

HUGO J. KROETZ.
